UNITED STATES PATENT OFFICE

WILLIAM F. HUTCHINSON, OF BOUND BROOK, NEW JERSEY, ASSIGNOR TO HIMSELF AND THE OLIVER WIRE COMPANY, OF PENNSYLVANIA.

WIRE-NAIL MACHINE.

SPECIFICATION forming part of Letters Patent No. 593,019, dated November 2, 1897.

Application filed November 5, 1896. Serial No. 611,098. (No model.)

To all whom it may concern:-

Be it known that I, WILLIAM F. HUTCHINSON, of Bound Brook, in the county of Somerset and State of New Jersey, have invented 5 certain new and useful Improvements in Wire-Nail Machines, of which the following is a full, clear, and exact description.

My invention relates to improvements in nail-machines, and particularly to machines 10 adapted to form nails from a continuous wire.

The object of my invention is to produce a comparatively simple machine in which rotary dieing-rolls are used and also a rotating 15 table to receive the partially-formed nails and complete the formation of them, this rotary principle being adapted to make nails with great rapidity and also form perfect nails.

A further object of my invention is to produce a machine which is entirely automatic 20 and not likely to get out of repair, to the end that the production of nails may be cheapened.

With these objects in view my invention 25 consists of certain features of construction and combinations of parts, which will be hereinafter described and claimed.

Reference is to be had to the accompanying drawings, forming a part of this specification, in which similar figures of reference indicate 30 corresponding parts in all the views.

Figure 1 is a broken vertical cross-section on the line 1 1 of Fig. 4 of my improved machine, showing the wire as it is fed into the machine and cut into nails. Fig. 2 is a broken 35 detail plan view, partly in section, of the carrying-table which revolves beneath the dieing-rolls and receives and finishes the partially-formed nails. Fig. 3 is a detail edge view, partly in section, of the said carrying-table. Fig. 4 is a central longitudinal section 40 on the line 4 4 of Fig. 1; and Fig. 5 is a detail view, partly in section, of the dies used in completing the nail-point after it has been partially formed by the dieing-rolls.

The machine has a suitable frame 10, which 45 carries the parallel and oppositely-arranged dieing-rolls 11, each of which is grooved, as shown at 12, to receive the wire or stock 13, and in the grooves of the rolls are transverse 50 dies 14, the distance between which corresponds to the length of a nail to be cut, allow-

ance being made for the formation of the head, and the opposite dies register so that as the rolls revolve and the dies meet, as shown in Fig. 1, they make an impression on 55 opposite sides of the wire, as the drawing clearly shows, thus forming two sides of a nail-point, the other two sides being formed by the dies below, as will be hereinafter described.

Obviously the rolls 11 may be driven in many ways, but, as illustrated, they are carried by shafts 15, which are journaled in suitable bearings and one of which connects by gears 16 and 17 with the main driving-shaft 65 18, this being also journaled on the frame and provided with a fly-wheel 19 or other suitable driver, and the second shaft 15 is geared to a gear-wheel 20 on the opposite shaft, as shown clearly in Fig. 4. The details of the driving 70 mechanism are not carried out, because it is obvious how the driving is accomplished and that the shafts can be rotated in many ways.

The dies 14 do not quite sever the wire 13, and after being incised it passes downward 75 through the guide 21, opposite a vertically-arranged die 22, which is held on the abutment or facing 23 of the bracket 24 by a face-plate 25, (see Figs. 4 and 5,) which is screwed to the bracket. The die 22 has an inverted-V- 80 shaped slot 22^a at the bottom, (see Fig. 5,) in which fits the opposite or male die 26, formed on the bar 27, these dies 26 and 27 being arranged in series on the table 28, which rotates on a vertical axis, so that the dies 26 successively engage the slot 22^a of the die 22. By 85 reference to Figs. 1 and 5 it will be observed that the planes of the sides of the slot 22^a are at right angles to the planes of the incisions made by the dies 14, so that as the nails 13^a 90 (see Fig. 1) are pushed by the dies 26 through the die 22 the points of the nails will be completed and said points will be four-sided.

When the partially-formed nails on the wire 13 are fed downward by the rolls 11, they 95 enter the annular groove or guide-slot 28^a (see Fig. 2) in the top of the table 28, and the nails are successively caught in the holes 29, (see the same figure,) which are formed partly in dies or case-hardened pieces 30 on one side 100 of the guide-slot 28^a and clamping-jaws 31 on the opposite side of the said slot, these jaws

being each pivoted at one end, as shown at 32, so as to swing horizontally in the slot 33 in the edge of the table 28. The case-hardened pieces 30 therefore act as fixed and the 5 clamping-jaws 31 as movable jaws. As the wire 13 is fed downward the partially-formed nail 13^a extends downward through the slot 28^a, and when the first hole 29 is reached the nail is clamped by the clamping-jaw 31, which 10 has a slightly-inclined or cam-shaped outer edge and which at this point is forced firmly inward against the nail by an abutment-roll 35, which is journaled on a vertical axis directly opposite the plane of the wire or nail, as 15 shown clearly in Fig. 4.

The nail is headed on the under side, and to prevent or rather resist the upward thrust during the heading operation rolls 36 are used, which bear on the upper side of the table 28, 20 opposite the part where the heading takes place, these rolls being journaled on the bracket 24, already referred to, which bracket slides vertically on the frame 10 and can be adjusted by the ordinary adjusting-wedges 25 37, (see Fig. 1,) which wedges have lugs 38, through which extend adjusting-screws 39, which enter the bracket 24 on opposite sides. The wedges overlap, and by moving them in and out the height of the bracket is regulated.

30 The table 28 can be rotated in any convenient way, but, as illustrated, it is secured to a vertical shaft 40, which is preferably mounted on ball-bearings 41 (see Fig. 4) and at the top connects by the bevel gear-wheels 42 and 35 43 with the main shaft 18.

When the nail 13^a drops into the table 28, is clamped, and has its point completed, as above specified, its lower end projects through the table and rests on one of a series of plungers 44, which plungers are carried in a rotating carrier 45, each plunger being vertically inovable and being prevented from falling out of the carrier by means of a pin 44^b on the plunger, which enters a slot 44^b in the 40 carrier. Any other suitable contrivance may be used for preventing the displacement of the plungers. The carrier 45 is rotated so that a plunger 44 will be moved upward and strike and form the head of the nail while

50 the nail is clamped, as above described, and, as illustrated, the carrier is secured to a vertical shaft 46, which connects by a gear-wheel 47 with a gear-wheel 48 on the shaft 40, and the said gear-wheel 48 also connects by idlers 55 49 and 50 with a gear-wheel 51 on the shaft 52, which shaft is driven by meshing beveled gears 53 and 54, connecting it with the main driving-shaft 18. This arrangement causes the shaft 40 to be driven from top and bottom, so that a high speed can be maintained and the strain of the shaft equalized. No novelty for this arrangement is claimed; however.

60 The plungers 44 travel over an idler-roll 55, which is arranged directly beneath the point where the nail 13^a is clamped, so that while the nail is held and just as its point is being

completed the plunger is forced upward by the said roll and striking against the lower end of the nail the head on the latter is formed by the blow. The roll 55 is carried on a shaft 56, which is journaled on a bracket 57, the latter being adjusted vertically by the ordinary adjusting and overlapping wedges 58, which are moved by the screws 59, extending 75 through lugs on the end of the wedges and entering the aforesaid bracket.

The operation of the machine is as follows: The wire 13, from which the nails are formed, is fed downward between the dieing-rolls 11, 80 the said rolls being self-feeding, although an independent feed may be used, if desired. As the wire proceeds the registering dies 14 make inclined impressions in the wire, the opposite sides thus forming two sides of a 85 nail-point, and as the wire is fed downward through the guide 21 passes opposite the die 22 and into the guide-slot 28^a of the table 28. Here as the table rotates it is clamped by one of the jaws 31, which is moved inward by the roll 35, as already described, and while the nail is securely held the plunger 44 strikes the lower end of it, the said plunger being forced up by the roll 55, and at practically the same instant the advance of the table 28 causes one of the dies 26 to push the nail through the slot 22^a of the die 22, thus completing the nail-point. As the nail is carried beyond the carrier 45 it drops from the table 28. It will be noticed that the dies 26 and 100 clamping devices advance in quick succession, and as the feed is timed so as to bring a nail in place as fast as the clamps are worked it will be seen that the nails are very rapidly formed, for the machine can be run at a comparatively high speed. The guide-slot 28^a in the table is important in this connection, as it enables the feed to be speeded high, and without some such contrivance it would be difficult to guide the nail into a clamping device.

I do not wish to limit my invention to the particular arrangement of parts illustrated, as I believe that my system of forming half the nail-points with the rotating dieing-rolls, then clamping the nail-blank, forming the remainder of the point, and making the head is broadly new, and that the details of construction can be changed considerably without affecting the spirit of the invention.

Having thus described my invention, I claim as new and desire to secure by Letters Patent—

1. A nail-machine comprising oppositely-arranged dieing-rolls constructed to form a portion of a nail-point, finishing-dies to form the remainder of the nail-point, a series of clamping devices to successively engage the nail-blanks and carry them through said finishing-dies, and a heading device acting while the nails are in the clamps, substantially as described.

2. A nail-machine comprising oppositely-arranged dieing-rolls constructed to form a

portion of a nail-blank between them, a stationary die lying essentially parallel with the blanks as they are discharged from the die-rolls, a series of clamps to receive the 5 blanks, a series of traveling finishing-dies movable with the clamps and adapted to pass through the stationary die to finish the nail-points, and reciprocating heading devices movable opposite the clamps, substantially 10 as described.

3. The combination of the stationary die, the traveling clamps opposite the die, the 15 movable dies arranged in series with the clamps and adapted to force the nail-blanks through the stationary die, and a heading device adapted to successively strike the nail-blanks as they are caught by the clamps, substantially as described.

4. The combination with the stationary die, 20 of the rotating table movable opposite the end of the die, the nail-clamps carried by the table, the dies carried by the table and arranged in series with the clamps, said table-

dies being adapted to pass through the stationary die, and a heading device to strike a 25 nail-blank when engaged by the clamps, substantially as described.

5. The combination of the stationary die, the rotating table, the clamps on the table, the dies on the table arranged to move 30 through the stationary die, the heading device to strike a nail-blank when engaged by the clamps, and bearing devices arranged on the table opposite the heading device to take the thrust, substantially as described. 35

6. The combination with the rotating table having a continuous guide-slot therein, of the jaws arranged at intervals on opposite sides of said guide-slot and adapted to close upon blanks held in the slot, substantially 40 as described.
